LIQUID BREAK CIRCUIT BREAKER

Henry Trencham, Ruislip, and Harold Ernest Cox, Dollis Hill, London, England, assignors to General Electric Company, a corporation of New York

Application January 7, 1936, Serial No. 57,968
In Great Britain January 7, 1935

4 Claims. (Cl. 200—150)

The present invention relates to liquid break circuit breakers of the impulse type, i. e., in which during separation of the contacts a positive flow of insulating liquid is produced between the contacts by means of a piston moved simultaneously with the contact separation whereby the arc formed when the breaker is interrupting a current is extinguished. In such a device the amount of energy used must be large when it is required to interrupt heavy currents. The pressure applied to the piston must be sufficient to accelerate the necessary volume of liquid to the requisite velocity and to do this against any back pressure which may result from gas formation at the contacts.

The present invention has for its object the improvement of circuit breakers of this kind by either reducing or compensating for the pressure set up by the formation of gas when interrupting a heavy short circuit.

The invention is particularly concerned with circuit breakers of the kind wherein the arc, between cooperating contacts when interrupting circuit, is drawn in a closely restricted space surrounding the contacts, and a jet of oil is forced transversely across the path of the arc.

Our invention will be more fully set forth in the following description referring to the accompanying drawing, and the features of novelty which characterize our invention will be pointed out with particularity in the claims annexed to and forming a part of this specification.

In the accompanying drawing are shown constructions embodying the invention, Fig. 1 being a transverse section through one form of the invention and Figs. 2, 3 and 4 representing sections of alternative constructions.

Referring to Fig. 1, there is illustrated an outer casing 1 supporting through an insulator 2 a housing 3 containing the fixed contact 4, the housing being in part supported from a second insulator 5 through which the lead to the fixed contact is brought through the wall of the casing 1. A second contact 6 is supported on an insulator 7 similarly mounted to insulator 5 on the upper wall of the casing 1, and forms the other terminal of the circuit breaker. Contact is made and broken between contacts 4 and 6 by means of a moving rod 8 which slidably engages the contact 6 and is moved into and out of engagement with the contact 4 by a horizontal motion brought about by a linkage enclosed in the spherical extension 9 of the casing 1, the extension 9 being attached to the casing through an intermediate cylindrical member 10.

The housing 3 enclosing the fixed contact 4 provides a cylindrical portion 11 which is open at the right-hand end to the inside of the housing 3 and within which reciprocates a piston 12 attached through an insulating rod 13 to the linkage 5 in the spherical extension 9. The left-hand end of the housing 3 is closed by a pair of spaced insulating plates 14, 15, which provide an aperture 16 through which the contact rod 8 is moved to engage the contact 4. The passageway 17 between 16 the plates 14, 15 communicates through an aperture 18 in the plate 14 with the left-hand side of the piston 12.

Between the outer face of a removable arcing tip 19 of the contact 4 and the adjacent face 15 of the insulating plate 14 is a venting passageway 20 which, it will be noticed, is in communication with the face of the piston 12 within the housing 3.

Thus the cooperating pair of contacts may consist of a rod contact moving axially in a closely fitting cylindrical space and engaging with a socket contact situated at one end of the cylindrical space, the arc being subjected to the action of a transverse jet of oil introduced by openings in the walls of the cylindrical space, conveniently situated for the purpose and communicating with the cylinder and piston, and with a venting space respectively.

In such a circuit breaker it will be seen that gas formed by the action of the arc will have the effect of tending to plug up the venting hole for the oil jet and to build up a back pressure against which the piston must act to force oil across the arcing space.

An electric circuit breaker of the impulse type 35 according to the invention has the moving contact withdrawn from engagement with the fixed contact through an aperture formed in a pair of spaced transverse members, the space between which forms a passageway into which the insulating liquid is forced by the piston during the circuit opening movement, a venting passage being provided for permitting the escape of gas from the space immediately adjacent the fixed contact. The venting passage may be in communication 40 with the side of the piston remote from that which provides the pressure in the insulating liquid for forcing it through the passageway. Alternatively, the venting passage may be in communication with an expansion chamber or may 45 be provided in the fixed contact itself.

When the contact rod 8 is moved in circuit-opening direction to the left from the position shown in chain lines in which it is in engagement with contact 4, the piston 12 is moved si- 55

multaneously in the same direction, thus providing a flow of insulating liquid such as oil with which the casing 1 is filled and a jet of oil is expelled through the passageway 17 across the path 5 of the arc formed between the contact 4 and the rod 8, thereby extinguishing the arc. The purpose of the passageway 20 is to ensure that the bubble of gas which is formed by the vaporization of the insulating liquid due to the heat of 10 the arc does not provide a back pressure tending to stop the jet of liquid since the gas can escape through this venting passage and provide a pressure on the side of the right hand piston which assists the piston in providing the flow of 15 oil. A bleeder aperture may be provided in the top of the housing 3 to enable it to refill with oil after a circuit opening movement has been made.

The circuit breaker has been illustrated with the contact movement in a horizontal plane, 20 but it is to be understood that it may equally well, and preferably is, arranged to operate with a vertical axis of contact separation. The description herein given will apply mutatis mutandis to either arrangement.

25 The linkage which causes movement of the contact rod 8 and the piston 12 will now be described. A transverse shaft 21 journaled in the wall of the extension 9 carries an arm 22 and is provided externally with an operating handle 30 which may be actuated manually or otherwise. The crank arm 22 is pivotally connected to an adjustable link 23 which is, in turn, pivoted to a lever 24. At the lower end, lever 24 is pivotally connected intermediate the ends of a link 25 35 which is pivotally mounted at its upper end at a fixed fulcrum 26 and is linked at its lower end near the middle of a link 27 which is pivotally connected at 28 to the contact rod 8. At its upper end the lever 24 is pivotally connected 40 to a floating lever 29 which is in turn loosely connected to the insulating rod 13 which actuates the piston 12. A pin 30 at the lower end of link 27 works in a slot in floating lever 29 which has the movement of its upper end controlled in one direction by an abutment 31.

45 The linkage is shown in the position in which the operating shaft 21 has been rotated counter-clockwise so as to extend spring 32 which biases the piston 12 to the left and it will be noted that further rotation counterclockwise of shaft 21 will cause lever 24 to rotate link 25 in a counter-clockwise direction, thereby rotating the link 27 clockwise and moving rod 8 to the right to cause 50 contact engagement. This movement will extend biasing spring 33, which biases the contact rod 8 in a circuit-opening direction. The breaker is now closed and the contact rod 8 is biased in the circuit opening direction and the piston 12 is similarly biased in a direction to cause the desired flow of oil across the arc formed when the contacts separate. Rotation of 55 shaft 21 will be affected to such an extent that crank arm 22 and link 23 will become slightly overset so as to hold the breaker in the circuit closed position. On rotating shaft 21 in a clockwise direction, the linkage will be released and the springs 32 and 33 will cause the movement of the piston 12 and contact rod 8 in a direction to the left, thereby opening the breaker contacts 60 and extinguishing the arc.

70 Fig. 2 shows a modification in which the jet of oil is produced by the piston 12 being located below the fixed contact 4 and the jet of oil being produced vertically upwards through the passageway 17. The head of oil which resists the flow of oil

through the passage 17 is thus reduced, the normal oil level being somewhat above the contact 4. In this modification, also, the venting passage 20 communicates with an expansion chamber 34 which is mounted at the upper side of the housing 5 3 and is mainly above the oil level. The expansion chamber 34 is provided with a bleeder aperture 35, which allows air to enter the expansion chamber and permits any oil which may have been forced 10 therein by the pressure of the gas to drain out of the expansion chamber.

In Fig. 3 is shown a further modification in which contact separation takes place in a vertical direction and in which the venting passage 20 communicates with a passage 36 formed in the 15 wall of the housing 3, the other details of the arrangement remaining mainly as described in connection with Fig. 1.

In Fig. 4, which is a further modification, the venting passage is provided by making the fixed 20 contact 4 hollow so that gas can escape directly through the passage in the centre of the contact.

Having now particularly described and ascertained the nature of our said invention and in what manner the same is to be performed we declare that what we claim is:—

1. An electric circuit breaker of the impulse type comprising means forming a chamber containing an arc-extinguishing liquid, relatively movable contacts separable within said liquid, 30 one of said contacts movable through a wall of said chamber, means forming a passage transverse to the path of said movable contact, a piston, one side of which is in communication with said chamber and the opposite side with said passage and actuating means for biasing said piston in a direction to cause a blast of arc-extinguishing liquid through said transverse passage and across the arc formed therein, the arc pressure generated in said chamber also acting on said one 40 side of said piston so as to aid said transverse blast.

2. An electric circuit breaker of the impulse type comprising means forming a chamber containing an arc-extinguishing liquid, relatively 45 movable contact structure separable within said liquid, said contact structure also adapted to draw an arc exteriorly of said chamber, means forming a passage transverse to said arc, a piston, one side of which is in communication with said chamber, 50 and the opposite side with said passage, and an actuating spring for biasing said piston in a direction to cause a blast of arc-extinguishing liquid through said transverse passage and across said arc, the arc pressure generated in said chamber 55 also acting on said one side of said piston so as to aid said transverse blast.

3. An electric circuit breaker of the impulse type comprising a casing forming an arc chamber containing an arc-extinguishing liquid, relatively movable contact structure separable within said liquid, said contact structure also adapted to draw an arc exteriorly of said chamber, insulating structure forming a passage transverse to said arc, a piston mounted for reciprocal movement within said casing and arranged so that one side of said piston is subjected to the arc pressure generated in said chamber, and the opposite side is in communication with said passage and actuating means common to said contact structure and piston for causing circuit opening movement of said contact structure and operation of said piston in a direction to cause a blast of arc-extinguishing liquid through said transverse passage and across the arc, the arc pressure gener- 70 75

ated in said chamber and acting on said one side of said piston also aiding said transverse blast.

4. An electric circuit breaker of the impulse type comprising an arc chamber containing an arc-extinguishing liquid, relatively movable contact structure adapted to draw an arc upon opening of the circuit within and exteriorly of said chamber, means forming a passage transverse to the exterior portion of said arc, a piston for driving a blast of arc-extinguishing liquid through

said passage for interrupting said arc, and actuating means for said piston, said piston being subject at one side to pressure generated in said arc chamber and being in communication at the opposite side with said passage whereby the arc pressure generated in said chamber tends to sustain said arc-extinguishing blast.
